UNITED STATES PATENT OFFICE

EDWARD ENGEL, OF BLOOMINGTON, ILLINOIS, ASSIGNOR TO MULLINS MANUFACTURING CORPORATION, OF SALEM, OHIO, A CORPORATION OF NEW YORK

WRINGER

Application filed December 2, 1931. Serial No. 578,454.

The object of my invention is to produce an improved mechanism by means of which the upper and lower rollers may be readily associated and dissociated.

5 The accompanying drawing illustrates my invention in an embodiment adapted for household use.

Fig. 1 is a vertical axial section in partial side elevation;

10 Fig. 2 is an end elevation with portions of the end walls of the base and cross-head broken away to show internal parts; and

Fig. 3 is an elevation of one of the connector plates.

15 In the drawing 10 indicates a main frame or base, conveniently formed of sheet metal, and comprising hollow end standards 11 open at their upper ends, oppositely extending aprons 12, guard wings 13, and an intermediate trough 14 perforated in its bottom at 15.

20 Each standard is provided with a vertical guide-way for the reception and support of a bearing block 16 for the lower roller 17 and for the reception of a bearing block 18 for the upper roller 19. At its lower end each guide way is provided with an end plate 20 to hold block 16 against outward axial displacement.

25 The above-described construction is well known in the art and, in detail, may be varied through a wide range.

The guard wings 13 are hollow and their interiors communicate with the lower interior of the interposed end standard 11 and arranged therein is a transversely arranged leaf spring 25 the ends of which engage abutments 26 within the base.

30 A cross-head 21, conveniently formed of sheet-metal, is so formed and proportioned as to sleeve slightly over the upper ends of standards 11. A plate 22, carried by the cross-head, serves to prevent outward axial displacement of bearing block 18, and a plate 45 23, also carried by the cross-head, overlies the block 18 and serves as an abutment against lateral displacement of the upper roller.

Journalized in the end walls of cross-head 50 21 are two short rock-shafts 31, 31, the inner

ends of which project into the interior of the cross-head.

Nonrotatively secured to the outer ends of shafts 31 are the ends of a U-shaped lever 32. Non-rotatively secured to the inner end 55 of each of shafts 31 is a crank arm 33, to the outer end of each of which is pivoted, at 33', the upper end of a connector plate 34 perforated at 35 to permit the shaft of the lower roller 17 to pass therethrough without interfering with vertical reciprocation of the connector plate.

The lower end of plate 34 is provided with a foot 34' in which is threaded a vertically adjustable pin 36, the upper end of which 65 underlies the middle of the adjacent spring 25. Pin 36 may be held in its vertical adjustment by a check-nut 36'. A portion 37, at the lower end of plate 34, is outturned and overlies a projection 38 carried by the base 70 so as to limit downward movement of plate 34 under the action of spring 25.

Crank arms 33, with their connector plates 34 form toggles which, when the crank arms 75 are placed vertically, eliminate rotative effect of springs 25 on shafts 31.

When lever 32 is swung to its medial vertical position the connector plates 34 are drawn upwardly so as to stress springs 25 and urge the cross-head downwardly upon 80 the bearing blocks 18 of the upper roller 19 with a desired initial pressure. Insertion of material between the rollers will cause upward lateral displacement of the upper roller and a further stressing of springs 25.

85 Slight displacement of lever 32 from its medial position permits springs 25 to exert a rotative force thereon so that it will be quickly snapped to one extreme or the other of its movement and the upper roller will 90 thus be instantly relieved from spring pressure.

When lever 32 is in either extreme position an upward swinging of the cross-head will cause an upward swinging of the crank arms 33 about their pivotal connections 33' so that the cross-head may be turned upside down thereby withdrawing the upper roller and exposing it for cleansing or withdrawal 95 from the cross-head.

I claim as my invention.

1. In a wringer structure, a base having hollow end standards, a cross-head bridging between the end standards, abutments in the cross-head to overlie bearing blocks for an upper roller, a U-shaped lever journalled in the cross-head and having portions projected into the cross-head at its ends, crank arms connected to said lever and within the cross-head, connectors pivoted to said crank arms and depending into the end standards, and spring means arranged in the base, said spring means being arranged to resist upward movement of the connectors.

2. In a wringer structure, a base having hollow end standards and communicating side wings, a cross-head bridging between the end standards, abutments in the cross-head to overlie bearing blocks for an upper roller, a U-shaped lever journalled in the cross-head and having portions projected into the cross-head at its ends, crank arms connected to said lever and within the cross-head, connectors pivoted to said crank arms and depending into the end standards, and spring means arranged in the base and extending transversely into the side wings, said spring means being arranged to resist upward movement of the connectors.

3. In a wringer structure, a base having hollow end standards, a cross-head bridging between the end standards, abutments in the cross-head to overlie bearing blocks for an upper roller, a U-shaped lever journalled in the cross-head and having portions projected into the cross-head at its ends, crank arms connected to said lever and within the cross-head, connectors pivoted to said crank arms and depending into the end standards, and leaf springs arranged transversely in the end standards, said spring being arranged to resist upward movement of the connectors.

4. In a wringer structure, a base having hollow end standards and communicating side wings, a cross-head bridging between the end standards, abutments in the cross-head to overlie bearing blocks for an upper roller, a U-shaped lever journalled in the cross-head and having portions projected into the cross-head at its ends, crank arms connected to said lever and within the cross-head, connectors pivoted to said crank arms and depending into the end standards, and leaf springs arranged transversely in the end standards

5. In a wringer structure, a base having hollow end standards and communicating side wings, a cross-head bridging between the end standards, abutments in the cross-head to overlie bearing blocks for an upper roller, shafts journalled in and projecting through the ends of the cross-head, a U-shaped lever connecting the outer ends of said shafts, a crank arm secured to the inner end of each shaft, a connector pivoted to each crank arm and depending into the adjacent end standard, and spring means arranged in the base and extending transversely into the side wings, said spring means being arranged to resist upward movement of the connectors.

6. In a wringer structure, a base having hollow end standards, a cross-head bridging between the end standards, abutments in the cross-head to overlie bearing blocks for an upper roller, shafts journalled in and projecting through the ends of the cross-head, a U-shaped lever connecting the outer ends of said shafts, a crank arm secured to the inner end of each shaft, a connector pivoted to each crank arm and depending into the adjacent end standard, and leaf springs arranged transversely in the end standards, said springs being arranged to resist upward movement of the connectors.

7. In a wringer structure, a base having hollow end standards and communicating side wings, a cross-head bridging between the end standards, abutments in the cross-head to overlie bearing blocks for an upper roller, shafts journalled in and projecting through the ends of the cross-head, a U-shaped lever connecting the outer ends of said shafts, a crank arm secured to the inner end of each shaft, a connector pivoted to each crank arm and depending into the adjacent end standard, and leaf springs arranged transversely in the end standards and extending into the side wings, said springs being arranged to resist upward movement of the connectors.

In witness whereof, I have hereunto set my hand at Bloomington, Illinois, this 21st day of November, A. D. one thousand nine hundred and thirty-one.

EDWARD ENGEL.

In witness whereof, I have hereunto set my hand at Bloomington, Illinois, this 21st ¹¹⁵ day of November, A. D. one thousand nine hundred and thirty-one.
